UNITED STATES PATENT OFFICE.

JEROME R. BUCHANAN AND ROBERT H. ABBOTT, OF LOS ANGELES, CALIFORNIA.

DESIGN FOR A WALL PLATE FOR LIGHTING FIXTURES.

Application filed December 12, 1925. Serial No. 15,735. Term of patent 7 years.

To all whom it may concern:

Be it known that we, JEROME R. BUCHANAN and ROBERT H. ABBOTT, citizens of the United States, both residing at Los Angeles, in the county of Los Angeles and State of California, have invented a new, original, and ornamental Design for a Wall Plate for Lighting Fixtures, of which the following is a specification, reference being had

to the accompanying drawing, forming a part thereof.

Figure 1 is a front view, and Figure 2 is a side view.

We claim:

The ornamental design for a wall plate for a lighting fixture as shown.

JEROME R. BUCHANAN.
ROBERT H. ABBOTT.
